AQUATIC TOBOGGAN SLIDE

Filed Oct. 8, 1923

UNITED STATES PATENT OFFICE.

CLYDE E. HOWARD, OF LOS ANGELES, CALIFORNIA.

AQUATIC TOBOGGAN SLIDE.

Application filed October 8, 1923. Serial No. 667,141.

To all whom it may concern:

Be it known that I, CLYDE E. HOWARD, a citizen of the United States, residing at Los Angeles, in the county of Los Angeles and State of California, have invented new and useful Improvements in Aquatic Toboggan Slides, of which the following is a specification.

My invention relates to amusement devices 10 and particularly to an aquatic toboggan slide in which a toboggan travels down an inclined track by gravity into a body of water.

The general object of my invention is to provide an aquatic toboggan slide, which 15 will be simple in construction and highly efficient in operation. A more particular object is to provide an aquatic toboggan slide which may be readily adjusted in length to extend into the water the proper distance 20 whether the water be nearer or further away from the main structure of the device.

Other objects and advantages will appear hereinafter and while I show herewith and 25 will describe a preferred form of construction, I desire to be understood that I do not limit my invention to such preferred form but that various changes and adaptations may be made therein without departing from the spirit of my invention as hereinafter 30 claimed.

Referring to the drawing:

Fig. 1 is a plan view of my toboggan slide.

Fig. 2 is a side elevation of my toboggan slide.

Fig. 3 is a plan view of two of the track sections.

Fig. 4 is a side view of said track sections.

Fig. 5 is a cross section of my toboggan slide taken on line 5—5 of Fig. 2.

40 In the drawing 1 indicates a gravity inclined track which comprises a main portion 2 mounted on a supporting structure 3, and lower sections 4 and 5, on which structure is a platform 6, at the upper end of said track, and a stairway 7 leading up to said platform. The structure 3 is built near a body of water 8 with the lower end of the main portion 2 of the track 1 near the edge of said body of water.

50 The main portion 2 and the sections 4 and 5 of the track 1 each comprises a pair of rails 9—9 on the inside of which are journaled at suitable intervals apart, rollers 10 by means of bolts 11, the rollers on said rails being opposite each other. Said rollers extend slightly above the rails 9—9 and over

said rollers travels a car in the form of a toboggan 12, the bottom 13 of which rests upon said rollers as shown in Fig. 5.

Rails 14—14 are secured to the sides of the 60 toboggan 12 at the lower edge thereof and extend downwardly over the sides of the track rails 9—9 whereby the toboggan is maintained on the track against lateral displacement.

65 Metal bars 15—15 are secured to the outside of the rails 9—9 at the lower end of the track portion 2 and extend a short distance below said end. A bolt 16 extends through said bars 15—15 and through one end of the 70 side rails 9—9 of an intermediate section 4, whereby said end of said section is detachably pivoted to said lower end of said track portion.

Metal bars 17—17 are secured to the outside of the rails 9—9 at the other end of section 4 and extend a short distance beyond said end of said section. A bolt 18 extends through the projecting ends of bars 17—17 and through one end of a terminal section 5, 80 whereby said section is horizontally pivoted to the lower end of section 4. The terminal section 5 is mounted on a pontoon 20 which floats in the water 8, and the outer or free end of this section is given a slight upward 85 turn as indicated at 21, which causes the toboggan 12 to leave the track almost parallel to the water surface so that the toboggan will not dive into the water.

The sections 4 and 5 may be readily detached upon removal of the bolts 16 and 18. One or more sections 4 may be employed in the track as conditions require, thus enabling the track to be adjusted in length to the water whether the water is nearer or further 95 away from the lower end of the track portion 2.

I claim as my invention:

1. A toboggan slide including a track composed of a stationary inclined portion, one or 100 more intermediate sections pivoted at one end to the lower end of said main portion, a terminal section pivoted at one end to the other end of said intermediate sections, and a pontoon on which said terminal section is 105 mounted, which pontoon floats in a body of water.

2. A toboggan slide including a track composed of a stationary inclined portion, a series of detachable intermediate sections 110 detachably pivoted at one end to the lower end of said main portion, a terminal section de-

tachably pivoted at one end to the other end of said series of intermediate sections, and a pontoon on which said terminal section is mounted, which pontoon floats in a body of 5 water.

3. A toboggan slide including a track extending downwardly, and over a body of

water, rollers on said track over which a toboggan travels, the rollers at the lowermost end of the track being successively journaled 10 one higher than the other to cause the toboggan to leave the track at a slightly upward inclination.

CLYDE E. HOWARD.
